Primary Examiner — Holly Baynham*Assistant Examiner* — Rhea Shields*(74) Attorney, Agent, or Firm* — Moss & Barnett(57) **CLAIM**

The ornamental design for a ophthalmoscope, as shown and described.

DESCRIPTION

FIG. 1 is a perspective view of our new design for an ophthalmoscope;

FIG. 2 is a front end view of the ophthalmoscope shown in FIG. 1;

FIG. 3 is a back end view of the ophthalmoscope shown in FIG. 1;

FIG. 4 is a left side elevation view of the ophthalmoscope shown in FIG. 1;

FIG. 5 is a right side elevation view of the ophthalmoscope shown in FIG. 1; and,

FIG. 6 is a top plan view of the ophthalmoscope shown in FIG. 1.

In the drawings, the broken lines are for the purpose of illustrating environment only and form no part of the claimed design.
